CLAIM

The ornamental design for a rope with its frame as shown and described.

DESCRIPTION

1. Rope with its frame

1.1 : Perspective

1.2 : Front

The claimed product refers to the appearance of the frame with a rope (paracord); Reproduction 1.1 shows the general appearance of the product; Accordingly, reproduction 1.2 of the claimed product shows their front view; Reproduction 1.2 of the product shows that the structure on which the rope is wound has an H-shape with a rectangular middle part; The rope (paracord) is tightly wound around the middle part of the frame in 1-3 layers.
